UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

SPLINT-DRYING MEANS FOR MATCH-MACHINES.

1,127,416.

Specification of Letters Patent.

Patented Feb. 9, 1915.

Application filed June 10, 1913. Serial No. 772,776.

To all whom it may concern:

Be it known that I, JOSEPH C. DONNELLY, a citizen of the United States, and resident of Barberton, in the county of Summit and State of Ohio, have invented certain new and useful Improvements in Splint-Drying Means for Match-Machines, of which the following is a specification.

This invention relates to splint-drying means for match machines, having reference more especially to continuous machines wherein an endless carrier receives the splints row by row and transports them through the match making path, including a bath of "impregnating" material adapted to render the splints non-glowing after the same, as finished matches, have been ignited and the flame extinguished.

The object of my invention is to provide for such machines a drying structure into and through which the wet splints, after they have been subjected to the bath of impregnating material, are carried and thereby effectually dried in a relatively short space of time.

An important feature of my invention resides in the provision of a drying chamber of such construction that the vapors arising therein from the splints and the air introduced to the chamber for the drying of the splints are discharged therefrom at different points in the travel of the splints, and thus the air, as rapidly as it becomes charged with moisture, is removed from the path of the splints and the latter in consequence are progressively subjected to the efficient drying action of the inflowing air.

In the form of embodiment of my invention herein illustrated the structure, as generally stated, comprises a drying chamber through which the splint carrier is directed: an air-egress conduit in communication with said chamber at different points in the path of travel of the carrier; a heater arranged within the chamber, and means whereby a current of air is supplied to the chamber.

The invention also comprehends various novel features of construction and arrangements of parts whereby advantages are secured, as will be hereinafter described and claimed.

In the drawings Figure 1 is a longitudinal vertical section of the drier, showing the "impregnation" tank and a portion of

the endless splint carrier. Fig. 2 is a transverse vertical section, as on the irregular line 2—2 of Fig. 1. Fig. 3 is a transverse horizontal section, as on the line 3—3 of Fig. 1. Fig. 4 is a partial end elevation of the lower part of the structure, the plates 34 being removed to expose parts otherwise concealed. Fig. 5 is a sectional detail, as on the line 5—5 of Fig. 3.

A designates a portion of an endless carrier by means of which rows of splints are transported in spaced relation to each other through the match making path. This carrier, in the form illustrated, comprises flexibly-connected plates provided with rows of perforations to receive and hold the ends of the splints; the adjacent edges of successive plates being slightly separated or spaced (as indicated at a) to permit the requisite flexure of the chain of plates without liability of the end rows of splints of adjoining plates contacting with each other.

B designates a tank in which "impregnating" liquid is contained, which tank is suitably supported beneath the path of the carrier. The track for this carrier is appropriately constructed (as at a') to effect the vertical movement of the traveling plates or sections of the carrier in respect to the top of the tank after the carrier leaves the splint-inserting station of the match machine, and thus the splints during their progress are periodically dipped into and raised from the liquid contents of the tank in order to effect the requisite impregnation of the splints.

The splint-drying structure through which travels the carrier with its load of wet impregnated splints, after leaving the tank B includes an inverted U-shaped frame 95 provided at intervals throughout its length with transverse openings 11. The carrier is impelled through the interior of this frame in a vertically extending loop, with the splints projecting inwardly, by means of suitably-disposed gear wheels 12 which mesh with the usual marginal rack teeth 13 of the carrier. The shafts 14 carrying the gear wheels are driven in any suitable manner.

The arched portion of the frame has bolted or otherwise secured thereto a trackway 15 for the support and guidance of the carrier, the back of the latter in its travel being maintained in close relation with the inner 110

wall of the frame. This wall is provided with suitably spaced ways 16 for the passage of the marginal rack teeth of the carrier. There is no permanent closure of the openings 11 in the wall of the frame by the opposing carrier, for the reason that the gaps or spaces (a) between the succeeding carrier plates progress across such openings and provide ample vent thereto.

- 10 The portion of the frame through which the carrier travels is inclosed by a suitable casing and a capacious drying chamber thus provided. The casing, in the present instance, comprises two side plates 17, an inverted U-shaped covering 18 and a bottom plate 19, the whole being bolted or otherwise tightly secured to the frame 10. The covering is adequately spaced from the internal frame to provide an intervening conduit 20 which merges with an outlet pipe 21 at the top of the casing, and the bottom plate is provided with a central opening which communicates with a depending intake pipe 22. Within this pipe is mounted 25 a fan 23, the shaft of which, having its bearings in brackets 24 bolted to the pipe 22, is provided with a pulley 25 which is driven from a suitable source of power, whereby a constant current of air can be supplied to 30 the drying chamber. Any other appropriate means for establishing a flow of air to the drying chamber may be substituted for that just described.

Arranged within the drying chamber are 35 several heat radiators 26, comprising in the present instance batteries or tiers of circulatory steam pipe systems, the pipes of which are preferably arranged in staggered relation to each other as shown. The radiators rest upon supporting bars 27 secured to the side plates of the casing, and each battery of pipes is provided with a valve 28 (Fig. 3) for regulating the admission of steam thereto; whereby any or all of the 40 batteries of radiators can be rendered active or idle as requirements may demand.

By the above-described construction it will be seen that a constant current of air 45 is established within the drying chamber and among the pipe systems therein so as to be thereby effectually heated, the pipes by their staggered arrangement effecting an extensive heating and diffusion of the ascending air; and that as the carrier, with its load of impregnated splints, enters and passes in its extended course through the chamber, the splints are subjected to the efficient drying action of the air. It will also be seen that the vapors arising from the 50 moisture in the splints, as well as the moisture charged air, pass directly into the conduit by way of the gaps in the carrier and the differently-disposed vents or openings in the frame, escaping thence through the outlet 21. Consequently the splints, as they

progress through the drying chamber from the inlet 29 to the exit 30 thereof, are not exposed to the prolonged action of the vapor and the moisture laden air, but instead they are subjected to the immediate and efficient 70 drying effect of the heat and air from the extensive radiating surfaces presented by the multiplicity of steam pipes.

The internal frame 10 is preferably provided with slide plates 31 for the respective 75 openings 11, whereby the latter can be closed or opened more or less to check or regulate the passage of air, etc., from the drying chamber to the conduit at predetermined 80 points throughout the course of the carrier, as conditions may require. In the present instance the plates 31 are adjustably secured to the outer side of the frame by thumb screws 32 passing through vertical slots 33 in the respective plates; and access to such plates is had through openings in the walls of the covering 18, which openings are closed by removable plates 34 suitably secured to the said walls, as by the thumb 85 screws 35.

In addition to the spaced openings 11 in the frame 10, communication is also preferably provided at intervals between the drying chamber and the conduit, by means of openings 36 and ducts 37 in the flanged 90 edges of said frame. These openings 36 can also be closed or opened more or less, as need may require, by means of plates 38 which are adjustably secured to the frame 10 by cap screws 39 passing through horizontal 95 slots 40 in said plates 38. As a means to deflect the heated air to and among the traveling splints preparatory to its escape to the conduit, inwardly-extending plates 41 are preferably secured at intervals to the flanged ends of the frame so as to lie adjacent the path of the splints in the carrier.

It is to be understood that I do not limit my invention to the exact details of construction shown and described, as the structure may be variously modified without departure from my invention.

I claim—

1. In splint-drying means for match machines having a splint carrier, a structure comprising a drying chamber, a conduit adjacent thereto with which said chamber communicates at different points throughout the length of said chamber, an air outlet from the conduit, a radiator confined within the drying chamber, means for supplying air to said chamber, and means for guiding a carrier chain through said chamber.

2. In splint drying means for match machines having a splint carrier, a structure comprising a drying chamber having its wall perforated at intervals, a conduit communicating with said chamber through the said perforated wall, an air outlet from the conduit, a radiator confined within the dry-

ing chamber, means for supplying air to said chamber, and means for guiding a splint carrier through said chamber.

3. In splint drying means for match machines having a splint carrier chain, a structure comprising an inverted U-shaped frame, a casing therefor constituting therewith a drying chamber and an air conduit, said chamber communicating with said conduit at different points throughout the length of the chamber, and said conduit having an air outlet at the top thereof, a radiator confined within said chamber, means for introducing air into the bottom of said chamber, and
- 10 means for guiding a splint carrier through said chamber.

4. In splint drying means for match machines having a splint carrier chain, a structure comprising an inverted U-shaped frame, a casing therefor constituting therewith a drying chamber and an air conduit, said chamber communicating with said conduit at different points throughout the length of the chamber and said conduit having an air outlet, radiator pipes confined within said chamber, means for supplying air to said chamber and among the radiator pipes, and means for guiding a splint carrier through said chamber.
- 20 5. In splint drying means for match machines having a carrier comprising flexibly connected splint holding plates, a structure comprising a drying chamber and an adjacent conduit with an intervening wall, said wall having spaced openings therein to provide communication between said chamber and conduit at different points throughout their length, and said conduit having an air outlet, a radiator confined within said chamber,
- 25
- 30
- 35

ber, means for supplying air to said chamber, and means for guiding a splint carrier through said chamber with the back of the carrier in close relation to the said wall.

6. In splint drying means for match machines having a splint carrier, a structure comprising a drying chamber and an adjacent conduit with an intervening wall having spaced openings therein to provide communication between said chamber and conduit at different points throughout their length, and said conduit having an air outlet, means for regulating said openings, a radiator confined within said chamber, means for supplying air to said chamber, and means for guiding a splint carrier through said chamber.

7. In splint drying means for match machines having a splint carrier, a structure comprising a drying chamber and an adjacent conduit with an intervening wall having spaced openings therein to provide communication between said chamber and conduit at different points throughout their length and said conduit having an air outlet, a radiator confined within said chamber, means for supplying air to said chamber, means for guiding a splint carrier through said chamber, and inwardly extending plates adjacent the longitudinal edges of the carrier for deflecting the air to and among the splints in the carrier.

Signed at Barberton in the county of Summit and State of Ohio this 5th day of June A. D. 1913.
